UNITED STATES PATENT OFFICE.

JAMES A. CAMERON, OF NEW YORK, N. Y.

MOVING-PICTURE MACHINE.

1,088,806.

Specification of Letters Patent. Patented Mar. 3, 1914.

Application filed January 8, 1912. Serial No. 669,995.

To all whom it may concern:

Be it known that I, JAMES A. CAMERON, a citizen of the United States, and a resident of the borough of Brooklyn, in the county of 5 Kings, city and State of New York, have invented certain new and useful Improvements in Moving-Picture Machines, of which the following is a specification.

The object of my invention is in general 10 to protect the film during its passage through the machine. For this purpose I propose to cover the film moving mechanism of the machine with a fireproof casing or shield, whereby the film will be inclosed and protected during its entire movement through 15 the machine. And in this connection one feature of my invention consists in building a fireproof casing in such way as to utilize the framework of the machine as a part of 20 the casing.

Various other objects and features of the invention will appear as the specification proceeds.

In the accompanying drawings I have 25 illustrated a preferred embodiment of my invention, but I would have it understood that various changes and modifications may be made therein without departing from the spirit and scope of the invention.

30 In the drawings: Figure 1 is a perspective view of the invention, the upper and lower film containers being broken away for want of room. Fig. 2 is a similar view with the door of the casing swung open. In this view the film moving mechanism of the machine is indicated in dotted lines. Fig. 3 is a perspective view like Fig. 1, looking at the opposite side of the machine. Fig. 4 is a plan view of a slightly modified form of the 35 invention, and Fig. 5 is a broken detail view of the modification illustrated in Fig. 4.

Like reference characters refer to corresponding parts throughout the several views.

The invention constitutes in a preferred 45 embodiment a substantially rectangular casing made up of the substantially parallel side walls 1 and 2 and the substantially parallel front and rear walls 3 and 4 respectively. This casing is made to inclose the 50 film moving mechanism of the machine, and in order to permit convenient access to such film moving mechanism, the casing is provided with a movable part or door. To allow of the greatest freedom in the "threading up" of the machine, this door is preferably made comparatively large, and in the

preferred form two whole sides of the casing are made to swing open as a door. Thus, as shown in the drawings, the two contiguous sides 1 and 3 are relatively fixed, while the two opposite sides 2 and 4 form in fact an angular door mounted on a pivot or pivots. These pivots in the present instance are shown as pintles 5 and 6 carried by the door, which engage in pivot openings in lugs 7 and 8 on the fixed side wall of the casing.

An important feature of my invention consists in utilizing the frame of the machine as a portion of the casing. Thus, as illustrated in the drawings, the fixed side wall 1 is in reality the side frame of the machine which serves as the support for the film moving mechanism, this mechanism being indicated in general by the figure 9. The film moving mechanism is thus supported on 75 the inner wall of the frame, while gearing 10 for operating such mechanism is disposed on the outer wall of the frame, as indicated in Fig. 3. When the frame is thus made to serve as a part of the casing, it is preferably 80 made substantially continuous so as to serve as a continuous wall. The front wall 3 which is also preferably rigid, may or may not be made integral with the fixed side wall. Preferably, as indicated, it is cast integral with the frame so as to in fact constitute an angular front portion of the frame. Both the upper film support 11 and the 85 lower film receiver 12 may be secured to and be supported direct upon the frame.

The rear-wall portion 4 of the door is provided with an aperture 13 to register with the exposure opening 14 of the machine, and the front wall 3 is provided with a corresponding opening 15. The door may also 90 have other openings therein to permit the projection of certain parts of the mechanism. For instance, it may have an opening 16 in its lower corner to permit the "framing" screw 17 to project therethrough. And 100 the door may also have an angular opening 18 in its upper portion for the passage of the pin 19 of the fire shutter mechanism. This fire shutter is indicated at 20, and it is conveniently supported by being pivoted in the 105 bushing 21 carried either by the door or by a fire shield 22 which is secured to the door. The fire shield may be secured to the door by screws 23 or other suitable fastening means, and is, as shown, preferably 110 mounted in spaced relation with respect to the door so as to provide an air space between the

door and the shield. The pin or arm 19 is, as shown best in Fig. 3, connected with the inner end of the pivot or journal 24 of the fire shutter, and this arm 19 when the door 5 is closed is adapted to be engaged by an operating member 25 which is acted upon by certain mechanism for controlling the opening or closing of the fire shutter. The operating member 25 may, as shown in Fig. 3, 10 be supported on a bracket 25' carried by the frame of the machine.

The upper and lower pivots or hinges of the door are preferably, as indicated in Fig. 2, arranged slightly out of vertical alignment, the lower one being offset outwardly 15 from the upper one, as in the nature of a gate hinge so that the door will have a natural bias or tendency to swing closed. A spring catch 26 or like securing device may be provided for securing the door in its closed position, and a stop 27 may be used for limiting the opening movement of the door.

In preparing the machine for operation, the door is swung open and the entire film 25 moving mechanism is thereby exposed. The film is then readily threaded through the machine, my invention not hindering at all in this process. With the door closed, the film is protected absolutely in its entire passage 30 through the machine, thereby eliminating all danger of fire or other injury to the film. By combining the film support and the film receiver with the machine, the film is protected during its entire passage from the 35 support to the receiver.

The stop 27 described above is preferably so disposed that when the door is swung open to its fullest extent, the angular side portion 2 will form a shield in line with the beam of 40 light issuing from the lantern or other source of illumination. This lantern is illustrated more or less diagrammatically at 28 in Fig. 1, from which it will be readily seen that the film engaged in the film moving mechanism will be protected from the heat of the lantern even when the door is open.

Inasmuch as in every moving picture machine the film moving mechanism is protected more or less by the frame of the machine, it will be evident that practically all 50 the advantages of the invention may be obtained by using a shield inclosing only the exposed portion of the film moving mechanism, instead of a casing completely surrounding the mechanism. Accordingly I have shown in Figs. 4 and 5 an embodiment illustrating this phase of the invention. Here there is shown combined with a moving picture machine of preferred type, a shield or 55 shielding element 29 pivotally mounted on a support 30 so as to swing on a substantially vertical axis in the nature of the door illustrated in the other views. This shield is in fact practically the equivalent of the door 60 to the fireproof casing, since, like the door, 65

it is preferably provided with angularly disposed side and rear wall portions 31 and 32 respectively, to cover the exposed side and rear portions of the film moving mechanism. The method of mounting the door may vary 70 but preferably it is arranged to swing on a substantially vertical axis, with the upper and lower pintles 33, 34 offset slightly with respect to each other, as shown in Fig. 5, so as to create a natural bias toward the closed or operative position. And instead of being mounted on a separate support 30, the door or shield may be hinged direct to the frame 75 35 of the machine. The shield constructed in this manner is in the nature of a door co-operating with the frame of the machine to inclose the film moving mechanism. With the shield in normal operative position, the film moving mechanism is protected both at the rear and at the side, and when the shield 80 is swung back, the side portion 31 of the shield is preferably so disposed as to intercept the light from the lantern or other source of illumination.

The moving picture machine may of course be operated manually or by power. It is customary to operate these machines by hand. Accordingly I have shown a crank for operating the same. This crank during its revolution swings in an arc past 90 the side of the machine, and hence across the face of the door or shield when the same is closed. In order to prevent the handle from interfering with the free opening and closing of the door or shield, I preferably 95 make this handle with an outwardly inclining or obliquely disposed shank portion 37, thereby carrying the handle 38 of the crank beyond the socket 39 of the crank to such an extent that no matter what the position of the crank may be, the handle or the shank of the crank will always lie outside the arc described by the opening movement of the door or shield. This feature of non-interference between the crank and the door 100 or shield is clearly illustrated in Fig. 4.

What is claimed, is:

1. In a moving picture machine, a frame embodying relatively fixed side and front walls, film moving mechanism supported on the fixed side wall, and a door pivoted to the fixed side wall embodying a rear and a side wall to coöperate with the fixed side and front wall to constitute a closed casing.

2. In a moving picture machine, a frame 120 embodying side and front portions, film moving mechanism supported on the side portion of the frame, and a door pivoted to the side portion, embodying rear and side sections corresponding in general to the front and side portions respectively of the frame, to form in combination therewith a substantially rectangular fireproof casing for the film moving mechanism, said door having an opening or openings therein to 125 130

permit projection of certain parts of the mechanism.

3. The combination with a moving picture machine having suitable film moving mechanism, of a casing inclosing the film moving mechanism and embodying relatively fixed angularly disposed side and front portions, together with an angular door pivoted to the relatively fixed side portion and coöperating with the relatively fixed side and front portions to constitute an inclosing casing.

4. The combination with a moving picture machine having suitable film moving mechanism, of a pivoted shielding element arranged to protect said film moving mechanism, the said shielding element being mounted to swing on a substantially vertical axis and having angular side walls to cover different sides of the film moving mechanism.

5. In combination with a moving picture machine having suitable film moving mechanism, and a lantern disposed in operative relation to the film moving mechanism, a pivotedly mounted shielding element arranged to swing on a substantially vertical axis having angular side portions to cover different sides of the film moving mechanism, and means limiting the opening movement of the shielding element to a position where one of the angular side portions of the same will be interposed between the lantern and the film moving mechanism.

Signed at New York city, in the county of New York and State of New York, this 26th day of December, A. D. 1911.

JAMES A. CAMERON.
